UNITED STATES PATENT OFFICE.

JESSE DITSON, OF LITTLETON, COLORADO, ASSIGNOR TO INGERSOLL-RAND COMPANY, OF JERSEY CITY, NEW JERSEY, A CORPORATION OF NEW JERSEY.

DRILL SHARPENER.

Application filed September 3, 1921. Serial No. 498,212.

To all whom it may concern:

Be it known that I, JESSE DITSON, a citizen of the United States, a resident of Littleton, county of Arapahoe, and State of 5 Colorado, have invented a certain Drill Sharpener, of which the following is a specification, accompanied by drawings.

This invention relates to drill sharpeners of the self contained type, having a vertically movable fluid actuated cross head which carries the upper half of the dies and other accessories, the lower cooperating half of said dies and accessories being carried upon the main cylinder frame.

15 The objects of the invention are to improve upon and simplify the construction of such machines, permit the piston for the cross head to be operated upwardly by constant pressure maintained in the base of the 20 machine as a pressure reservoir, so that no air is consumed on the raising stroke, enable all the sharpening operations to be controlled by a single throttle valve and manually actuated lever, and produce ample 25 clamping pressure without excessive shock to the machine.

Further objects of the invention will hereinafter appear and to all of these ends the 30 invention consists of the features of construction, arrangement of parts and combinations of elements, substantially as hereinafter fully described and claimed in this specification, and shown in the accompanying drawings, in which

35 Figure 1 is a longitudinal sectional elevation of a drill sharpener.

Figure 2 is a detail longitudinal sectional elevation partly broken away of that portion of the machine including the throttle valve 40 chest showing the throttle valve in another position.

45 Figure 3 is a detail vertical sectional elevation through the throttle valve chest at right angles to the view shown in Figure 1 with the valve in still another position.

Figure 4 is a side elevation partly in longitudinal section of the machine taken at right angles to Figure 1.

50 Figure 5 is a detail longitudinal sectional elevation through the hammer cylinder showing the hammer in a different position from that indicated in Figure 4.

55 Figure 6 is a side elevation partly in longitudinal section on the line 6—6 of Figure 7, the view being taken from the same

side of the machine as that shown in Figure 4, and

Figure 7 is a partial top plan view of Figure 6.

Referring to the drawings, the machine 60 comprises the base A having a main cylinder frame B suitably secured thereto as by means of the studs C and nuts D. A cross head rod E is movable vertically in the main cylinder frame B and carries a cross head F 65 at its upper end and a piston G at its lower end, operating in the cylinder bore H. The piston G has the reduced extension J sleeved over the reduced end K of the cross head rod E and suitably secured to the rod E by 70 means of the nut L and locking key O. The piston extension J is guided in the downwardly extending guide portion P of the frame and the hollow base A is closed at its lower end as by means of the base plate Q. 75 Motive fluid, as air under pressure, is admitted to the hollow base A, which forms a reservoir, through the inlet R and in accordance with my invention constant pressure is maintained within the hollow base acting 80 against the smaller end of the piston, tending to move said piston upwardly for the raising stroke. No air is admitted within the large cylinder bore H beneath the piston head G for the raising stroke, but said space 85 is open to atmosphere and means are provided for cushioning the downward stroke of the piston when live air is admitted above the main piston head G for the downward stroke. The distribution of motive fluid 90 from the hollow base or constant pressure reservoir for the operation of the machine, is controlled by a throttle valve S movable in the valve chest T and controlled by the manually operated handle U.

95 The provision of a constant pressure reservoir of motive fluid within the hollow base A enables me to use a comparatively long and small supply pipe connected to the inlet R of the reservoir. In operation, a cylinder 100 of comparatively large size may be supplied in a rapid manner from the reservoir in the base without a substantial drop in pressure. The reservoir is connected by a passage V in the main cylinder casing to a port in the 105 valve chest T which opens directly into the cylinder above the piston G when the controlling throttle valve S is in a given position. By reason of the fact that no air is admitted beneath the piston G on the rais- 110

ing stroke and no air is consumed on said stroke, the construction of the throttle valve S and throttle valve chest T is much simplified.

- 5 The throttle valve S is provided with the heads W and X connected by the stem Y, and a bell crank Z pivoted at one end to the throttle valve by means of the pin a and connected at the other end to the hand lever 10 shaft b, enables the throttle valve to be raised and lowered by rocking the lever U. The lever U may be clamped to the shaft b as by means of the split socket c and bolt d.

When the valve lever U is in central or 15 neutral position, as indicated in Figure 1 which is the position 1 indicated in dotted lines in Figure 3, the valve head W closes communication between the supply passage V from the reservoir in the base, and the space above the piston head G is open to 20 atmosphere through the passage e communicating with the valve chest and thence around the stem Y of the valve to the small port f and then through the passage g in 25 the wall of the valve chest to the port h communicating with the exhaust pipe j. The space beneath the piston head G is also open to atmosphere through the passage k communicating with the valve chest, and 30 the passage g. The piston G is in its uppermost position due to the constant pressure on the smaller pressure area constituted by the lower end of the piston shank and cross head rod within the constant pressure reservoir.

Movement of the operating handle U from the neutral position to the position indicated in full lines at 2 in Figure 3, admits live air above the main piston head G to carry 40 the piston and cross head downwardly, but in passing from position 1 to position 2 indicated in Figure 3, the handle U passes through the intermediate position 1^a indicated in detail in Figure 2. In Figure 2, the valve has been moved upwardly a sufficient distance to open communication between the passage V and the passage e, past the stem Y of the valve, so that motive fluid passes above the piston head G and 45 forces the piston downwardly. The descent and blow of the piston G is cushioned, owing to the fact that the exhaust from beneath the piston head G passing out through the passage k and the small passage g in the 50 wall of the valve chest T, is throttled at this point in the movement of the valve. Continued movement of the hand lever U to the second position indicated in Figure 3, raises the valve sufficiently to permit the 55 exhaust from beneath the piston head G to pass out directly underneath the valve head X to atmosphere through the exhaust pipe j, instead of through the throttling passage g.

Continued movement of the valve handle 60 U to the third position as indicated in Fig-

ure 4, which is the piston shown in dotted lines at 3 in Figure 3, moves the valve S upwardly still further and admits live air from the passage V around the valve stem Y to a supply passage o in the frame of the machine leading to the hammer cylinder p for actuating the dolly q, which is shown in Figures 4 and 5 operating upon the drill steel r held within the dies s, carried by the cross head F and the main cylinder frame B respectively.

The hammer cylinder p may be mounted on the main cylinder frame B, as by means of the clamping plates t and bolts u. The hammer cylinder p is provided with a back head v and a front head w, which front head forms a guide for the dolly q, and a ring or bushing x is inserted within the cylinder rearwardly of the front head w. The parts of the hammer cylinder are held together by the usual side bolts y having springs z and nuts 6. The hammer piston 7 is preferably of the valveless type, and the arrows in Figures 4 and 5 sufficiently indicate the distribution of motive fluid for actuating a hammer and operating the dolly when the valve lever U is in the position indicated in Figure 4. The usual dolly spring 8 is provided for the dolly.

By reversing the rocking movement of the valve lever U and returning said lever from position 3 through position 2 and 1^a to the neutral position 1, all as indicated in Figure 3, the cylinder bore H above the piston head G will be exhausted to atmosphere and the constant pressure on the reduced shank of the piston will raise the cross head F to the position indicated in Figure 1.

By rocking the valve handle U backwardly to the position indicated in full lines in Figure 6, and in dotted lines indicated at 4 in Figure 3, an arm 9 on the valve lever U will bear upon and force downwardly the valve stem 10 of a spring pressed blow valve 11 which is normally held to its seat 12 by the spring 13 and live air will be admitted from the valve chest T to a passage 14 leading to a blow head 15 having downwardly directed apertures 16 which direct the air blast upon the dies s to clean them for the next operation.

I claim:

1. In a drill sharpener, the combination of a hollow base maintained under substantially constant fluid pressure, a main cylinder frame mounted on said base, a cross head rod movable vertically in said cylinder frame and constantly subjected to the pressure in the base tending to move the said rod in one direction, a cross head and a piston head carried by said rod, a valve chest mounted on the cylinder frame and a throttle valve in said chest for intermittently supplying motive fluid from the base

- to the cylinder bore above the piston head for actuating the cross head and rod downwardly, the under side of said piston head being open only to atmosphere, and means 5 for throttling the escape of air from beneath the piston head on the downward stroke to cushion the piston head.
2. In a drill sharpener, the combination of a hollow base constituting a pressure 10 reservoir, means for maintaining motive fluid under constant pressure in said reservoir, a main cylinder frame mounted on said base, a cross head rod movable vertically in said cylinder frame and extending 15 into the base, the lower end of the cross head rod being thereby subjected to constant fluid pressure tending to raise it, a cross head on said rod, a piston head in said rod reciprocating in the bore of the 20 cylinder frame, and means for supplying motive fluid from the base reservoir to actuate the piston head downwardly, while at the same time maintaining the under side of the piston head open only to atmosphere.
- 25 3. In a drill sharpener, the combination of a hollow base, constituting a pressure reservoir, means for maintaining motive fluid under constant pressure in said reservoir, a main cylinder frame mounted on 30 said base, a cross head rod movable vertically in said cylinder frame and extending into the base, the lower end of the cross head rod being thereby subjected to constant fluid pressure tending to raise it, a cross head on said rod, a piston head in said rod reciprocating in the bore of the cylinder frame, means for supplying motive fluid from the base reservoir to actuate the piston head downwardly while at the same time 35 maintaining the under side of the piston head open only to atmosphere, including means for throttling the escape of air from beneath the piston head on the downward stroke for cushioning the piston head.
- 40 4. In a drill sharpener, the combination of a base, a main cylinder frame mounted on said base, a fluid actuated cross head rod movable vertically in said cylinder frame, a cross head carried by said rod, co- 45 operating dies carried by the cross head and cylinder frame, a blow head located on the cylinder frame adjacent said dies, and a throttle valve for controlling the distribution 50 of fluid pressure in the machine including the supply of fluid to the said blow head.
- 55 5. In a drill sharpener, the combination of a base, a main cylinder frame mounted on said base, a fluid actuated cross head rod movable vertically in said cylinder frame, a cross head carried by said rod, cooperating dies carried by the cross head and cylinder frame, a blow head located on the cylinder frame adjacent said dies, a throttle valve for controlling the distribution 60
- of fluid pressure in the machine, a blow head valve adjacent said throttle valve, and means for opening the blow head valve to supply fluid pressure to the blow head when said throttle valve is moved to a given position.
6. In a drill sharpener, the combination of a base, a main cylinder frame mounted on said base, a fluid actuated cross head rod movable vertically in said cylinder frame, a cross head carried by said rod, a fluid actuated hammer mounted on the cylinder frame, a fluid supply passage in the cylinder frame leading to the said hammer, a valve chest on the cylinder frame and a throttle valve in said chest for controlling the distribution of motive fluid for actuating the cross head and for controlling said supply passage leading to the hammer.
7. In a drill sharpener, the combination with a hollow base forming a motive fluid reservoir, a main cylinder frame mounted on said base having a smaller cylinder opening into said reservoir, a cross head rod movable vertically in said cylinder frame and constantly subjected to the pressure in the base tending to move the rod in one direction, a cross head and a piston head carried by said rod and means for supplying motive fluid to the piston for moving the cross head rod and cross head in the opposite direction.
8. In a drill sharpener, the combination of a hollow base forming a motive fluid reservoir, a main cylinder frame mounted on said base having a large cylinder bore and a small cylinder bore extending into said reservoir, a cross head rod movable vertically in said cylinder frame and constantly subjected to the pressure in the reservoir tending to move the rod upwardly, a cross head carried by said rod, a piston head on said rod operating in the larger bore of said main cylinder frame and means for intermittently supplying motive fluid to the larger cylinder bore above the piston head for actuating the cross head rod and cross head downwardly.
9. In a drill sharpener, the combination of a hollow base forming a motive fluid reservoir, a main cylinder frame mounted on said base having a large cylinder bore and a small cylinder bore extending into said reservoir, a cross head rod movable vertically in the smaller bore of said cylinder frame and constantly subjected to the pressure in the reservoir tending to move the rod in one direction, a cross head, a piston head carried by the rod and operating in the larger bore of the cylinder frame, means for supplying motive fluid to the piston for moving the cross head rod and cross head in the opposite direction and means for cushioning the piston head within the larger bore of the cylinder frame as the pis-

ton head reaches the end of its stroke in said opposite direction.

10. In a drill sharpener, the combination of a hollow base forming a motive fluid reservoir, a main cylinder frame mounted on said base having a large cylinder bore and a small cylinder bore extending into said reservoir, a cross head rod movable vertically in said smaller bore and constantly subjected to the pressure in the reservoir tending to move the rod upwardly, a cross head carried by the rod, a piston head on said rod operating in the larger bore of the cylinder frame, means for intermittently supplying motive fluid to the large cylinder above the piston head for actuating the cross head rod and cross head downwardly and means for cushioning the piston head within the cylinder frame as the piston reaches the end of its downward stroke.

11. In a drill sharpener, the combination of a hollow base forming a motive fluid reservoir, a main cylinder frame mounted on said base and having a large cylinder bore and a small cylinder bore extending into said reservoir, a cross head rod movable vertically in said smaller bore and constantly subjected to the pressure in the reservoir tending to move the rod upwardly, a cross head carried by the rod, a piston head on the rod operating in the larger bore of the main cylinder frame, means for intermittently supplying motive fluid to the larger bore above the piston head for actuating the cross head rod and cross head piston downwardly and means for throttling the escape of air from beneath the piston head for cushioning the stroke as the piston reaches the end of its downward stroke.

12. In a drill sharpener, the combination of a hollow base forming a motive fluid reservoir, a frame on said base having a large cylinder bore and a small bore extending into said reservoir, a cross head and a vertically movable cross head rod operating in the smaller bore and constantly subjected to the pressure in the reservoir for moving the cross head and rod upwardly.

13. In a drill sharpener, the combination of a hollow base forming a motive fluid reservoir, a main cylinder frame on said base having a large bore and a small bore extending into said reservoir, a cross head, a vertically movable cross head rod operating in the smaller bore and constantly subjected to the pressure in the reservoir for moving the cross head and rod upwardly and means for controlling the supply of motive fluid from said reservoir for actuating the cross head and rod downwardly.

14. In a drill sharpener, the combination of a hollow base forming a motive fluid reservoir under substantially constant pres-

sure, a main cylinder frame having a large bore and a relatively smaller bore extending into said reservoir, a cross head, a vertically movable cross head rod operating in the smaller bore and constantly subjected to the pressure in the base for moving the cross head and rod upwardly, means for supplying motive fluid from the reservoir for actuating the cross head and rod downwardly and means for cushioning the downward stroke of the cross head.

15. In a drill sharpener, the combination of a hollow base forming a motive fluid reservoir under substantially constant pressure, a main cylinder frame on said base having a main bore and a relatively smaller bore extending into said reservoir, a cross head, a vertically movable cross head rod operating in said smaller bore and constantly subjected to the pressure in the reservoir for moving the cross head and rod upwardly, a piston head on said cross head rod operating in the larger bore and means for supplying motive fluid from the reservoir for actuating the piston head and rod downwardly.

16. In a drill sharpener the combination of a hollow base forming a motive fluid reservoir under substantially constant fluid pressure, a main cylinder frame on said base having a large bore and a relatively smaller bore extending into the reservoir, a vertically movable cross head rod constantly subjected to the pressure in the reservoir for moving the cross head and rod upwardly, a piston head on said cross head rod operating in the larger bore, means for supplying motive fluid from the reservoir for actuating the piston head and rod downwardly and means for throttling the escape of air from beneath the piston head on the downward stroke to cushion the piston head.

17. In a drill sharpener, the combination of a hollow base forming a motive fluid reservoir under substantially constant fluid pressure, a main cylinder frame mounted on said base having a large bore and a relatively smaller bore extending into the reservoir, a cross head rod movable vertically in the smaller bore and constantly subjected to the pressure in the reservoir tending to move the rod in one direction, a cross head on said rod and a piston head carried by the rod for operating in the larger bore, a valve chest mounted on the cylinder frame and a throttle valve in said chest for intermittently supplying motive fluid from the reservoir to the larger bore above the piston head for actuating the cross head and rod downwardly.

In testimony whereof I have signed this specification.

JESSE DITSON.
